UNITED STATES PATENT OFFICE.

EDWIN STANTON JOHNSON, OF LINCOLN, NEBRASKA.

DRAWING INSTRUMENT.

SPECIFICATION forming part of Letters Patent No. 768,997, dated August 30, 1904.

Application filed February 12, 1904. Serial No. 193,275. (No model.)

To all whom it may concern.

Be it known that I, EDWIN STANTON JOHNSON, a citizen of the United States, and a resident of Lincoln, in the county of Lancaster 5 and State of Nebraska, have invented a new and Improved Drawing Instrument, of which the following is a full, clear, and exact description.

My invention relates to drawing instruments 10 used for certain special purposes to be referred to.

The objects of my invention are to provide a drawing instrument which is simple in construction and cheap to manufacture and is 15 capable of use for drawing ellipses and circles of various sizes.

Reference is to be had to the accompanying drawings, forming a part of this specification, in which similar characters of reference indicate 20 corresponding parts in all the figures.

Figure 1 is a perspective view of a preferred form of my invention, showing its use for drawing an ellipse. Fig. 2 is a plan view of the same. Fig. 3 is a sectional view on the 25 line 3 3 of Fig. 2, partly in elevation. Fig. 4 is a sectional view on the line 4 4 of Fig. 2, and Fig. 5 is a sectional view on the line 5 5 of Fig. 2.

In the drawings, 10 represents the body of 30 the instrument, having attached thereto or formed integral therewith, as preferred, at the ends or in any desired position projecting points 11, of rubber or other suitable material. These projections or corrugations are 35 designed for the purpose of preventing slipping and to do away with the present necessity of passing pointed fasteners through the paper when the instrument is used in order to draw curves. The body of the instrument is 40 also preferably provided with a long slot 12, extending from one end of the body to the other, for the purpose of receiving projections upon the two slides 13 and 14 and securing them in position.

45 15 is a screw passing through the slide 13 and screwing into a bottom piece 16 in such a manner as to secure the slide in any adjusted position to the body part of the instrument,

as shown in Fig. 4. 17 is a similar screw for holding the slide 14 in position. 50

Upon the slide 13 is a small projection or other device 18, perforated to hold the end of a flexible cord, string, or wire 20, the other end of the flexible connection 20 being held by a similar device 19 on the slide 14. 21 55 represents a pencil which is adapted to be guided by this flexible connection.

Upon the slide 14 is preferably placed a spring 22, having a bar 23 projecting into the projection 19, as shown in Fig. 5, for the 60 purpose of holding the cord in position. This spring is attached to the slide 14 by means of a set-screw or similar device 24. Upon one edge of the body 10 is formed a graduation 25, extending in opposite directions from a central 65 zero-point.

It will be readily observed that an instrument constructed in accordance with the principles herein set forth will be very simple, compact, and durable; that it will be capable 70 of use for drawing ellipses of all shapes and sizes within the limits prescribed by the length of the body-piece 10, which can be made in various sizes to suit different needs, so that it can also be used for drawing semicircles of 75 any desired radius by the simple expedient of setting the two slides 13 and 14 in contact at their contiguous edges, which will bring the two points of attachment of the flexible connection 20 into substantial coincidence. The 80 flexible connection 20 is designed to be adjusted in length at the projection 19 through the instrumentality of the spring 22 and the bar 23.

I do not wish to be limited to the exact form 85 shown in the drawings, as many modifications may be made therein without departing from the spirit of my invention as it is set forth in the appended claims.

Having thus described my invention, I claim 90 as new and desire to secure by Letters Patent—

1. In a drawing instrument, an apertured plate, a pair of holders adjustably secured thereto, and means for adjustably securing a flexible connection to said holders, comprising 95 a stud bearing on said connection, and a

spring for normally holding said stud firmly in contact with the connection.

2. In a drawing instrument having ways, the combination of a pair of plates mounted above said ways, adapted to slide on the ways independently of each other, and each having a detachable bottom piece adapted to slide in said ways and having means for attaching a flexible connection thereto, comprising a stud, and means for causing the stud to bear on the

flexible connection, with means for fastening both of said bottom pieces to the ways at any point.

In testimony whereof I have signed my name to this specification in the presence of two subscribing witnesses.

EDWIN STANTON JOHNSON.
